ATTORNEY.

UNITED STATES PATENT OFFICE.

HENRY H. SCHOLL, OF ST. LOUIS, MISSOURI.

LADY'S HAT-FRAME.

No. 926,360.

Specification of Letters Patent. Patented June 29, 1909.

Application filed February 3, 1909. Serial No. 475,854.

To all whom it may concern:

Be it known that I, HENRY H. SCHOLL, citizen of the United States, residing at St. Louis, State of Missouri, have invented certain new and useful Improvements in Ladies' Hat-Frames, of which the following is a full, clear, and exact description, reference being had to the accompanying drawings, forming a part hereof.

10 My invention has relation to improvements in ladies'-hat frames; and it consists in the novel details of construction more fully set forth in the specification and pointed out in the claims.

15 In the drawings, Figure 1 is a side elevation of a modern hat frame showing my invention applied thereto; Fig. 2 is an enlarged section on line 2—2 of Fig. 1; Fig. 3 is a projection of Fig. 2; Fig. 4 is a view similar 20 to Fig. 2 but showing the ends of the tie wire or loop in overlapped relation; Fig. 5 is a projection of Fig. 4; Fig. 6 is an enlarged section on the diagonal line 6—6 of Fig. 1, looking squarely against the tie loop; and Fig. 7 is 25 a sectional view showing the prevailing method of tying the cross wires on hat frames.

The object of my invention is to so unite 30 the intersecting wire members of a ladies'-hat frame that no sharp points or barbs will project to injure the hands of the trimmer by whom the frame is covered, the object sought being to produce a joint which shall be perfectly smooth, thereby enhancing the value 35 of the frame, and permitting a more rapid handling thereof.

The advantages of the invention will be better apparent from a detailed description thereof which is as follows:—

Referring to the drawings, F represents a 40 conventional hat-frame of the kind referred to, and C the detachable crown, constituting a supplemental frame which is secured by the trimmer to the main frame by stitches or any other convenient manner known to the 45 trade. Both the main frame and the crown are composed of intersecting wires *a* and *b* respectively, the ends of the wires *a* being looped about the terminal wires *b* as shown, each of the wires *b* overlapping at their ends

which are tied either by a thread wrapped 50 about such overlapped ends, or they may be secured by the wire loop forming the subject matter of the present invention as presently to be described.

Throughout the body of the frame at 55 points where the wires *a* and *b* intersect, it has been customary to tie the points of intersection or joints by means of a short piece of wire looped across the joint, the ends of the wire being brought together, and then 60 twisted, the twisted ends however pointing outwardly from the frame so that they scratch the hands of the trimmer. An example of this prevailing method is illustrated in Fig. 7 where *t* represents the tie wire 65 looped across the joint or intersection of the wires *a* and *b*, the twisted ends pointing outwardly from the body of the frame.

My invention contemplates the elimination 70 of the sharp points of the fastening or tie wire and this I accomplish by the construction shown in Figs. 1 to 6 inclusive. As stated above, the wires *a* and *b* intersect along the body of the frame. At each point of intersection or joint I wrap or loop a fastening or tie wire *e* with the ends of the fastener pointing inwardly, whereupon the loop is clenched about the wires *a*, *b*, the ends being either in abutting relation as shown in 75 Figs. 1 to 3 and 6 or in overlapped relation 80 as shown in Figs. 4 and 5, but always forming a closed ring with the ends of the ring always well within the boundaries of the curve assumed by the fastening wire or tie loop and never protruding beyond the general curvature of such wire, and thereby forming no projections. In this way no sharp points protrude from the body of the frame to injure the hands of the trimmer. 85

In my improvement the ends of the tie 90 loop *e* are generally on the inside of the frame, instead of on the outside as is the case with the prevailing method of tying shown in Fig. 7.

Having described my invention what I 95 claim is:—

1. A hat frame composed of intersecting wires, and a wire tie loop wrapped diagonally

about the point of intersection, with ends clenched to the wires and overlapping one another, and confined to the general curvature of the loop.

5. 2. A hat frame composed of intersecting wires, and a wire tie loop wrapped diagonally about the point of intersection, with ends on the inside of the frame clenched to the wires

and overlapping one another, and confined to the general curvature of the loop. 10

In testimony whereof I affix my signature, in presence of two witnesses.

HENRY H. SCHOLL.
